RIFLE MOUNTED KNIFE SHARPENER OR SIMILAR ARTICLE

William H. Pfeiffer, 307 Lone Star Road,
Nampa, Idaho 83651

Filed June 23, 1969, Ser. No. 17,821

Term of patent 14 years

Int. Cl. D8—02

U.S. Cl. D8—93

FIG. 1

FIG. 2

FIG. 3

FIG. 4

FIG. 1 is a side elevational view of the rifle mounted knife sharpener or similar article embodying my new design;

FIG. 2 is a front elevational view of the within invention;

FIG. 3 is a left front isometric view thereof; and

FIG. 4 is a left rear isometric view of the rifle mounted knife sharpener or similar article.

The figures drawn in broken lines are shown for illustrative purposes only.

I claim:

The ornamental design for a rifle mounted knife sharpener or similar article, substantially as shown and described.
